COMPRESSOR FOR REFRIGERATING APPARATUS

Herman M. Goldberg and Arvid E. Karlberg, Chicago, Ill., assignors to Chicago Seal Co., Chicago, Ill., a corporation of Illinois

Application May 3, 1944, Serial No. 533,843

3 Claims. (Cl. 230—58)

1

This invention relates to improvements in compressor units, particularly adapted, though not necessarily limited in use, for refrigerating apparatus.

Heretofore, with apparatus of this character it has been customary to enclose the motor for operating the compressor, within the compressor casing, with the result that it has been necessary, in order to gain access to the motor, to dismantle a considerable part of the compressor casing.

It is one of the objects of the present invention to overcome these difficulties and objections, and to provide an improved unit of this character, in which the motor is disposed outside of the compressor casing, and in position where access may be readily had thereto, without disturbing or opening the compressor casing.

A further object is to provide an improved compressor unit of this character, in which the motor is mounted upon the main compressor shaft, the fan being also mounted upon the same shaft, thereby dispensing with a separate motor for operating the fan.

A still further object is to provide, in a compressor unit of this character, an improved shaft seal to which access may be had for repair or replacement, upon removal of the external motor, without disturbing or opening the compressor casing, and to reduce the number of bearings to a minimum, thereby reducing the cost of production and of operation, without impairing the efficiency of the unit.

To the attainment of these ends and the accomplishment of other new and useful objects as will appear, the invention consists in the features of novelty in substantially the construction, combination and arrangement of the several parts, hereinafter more fully described and claimed, and shown in the accompanying drawing illustrating this invention, in which

The figure is a vertical sectional view of an apparatus of this character, constructed in accordance with the principles of this invention.

In the drawing, the numeral 10 designates, generally, a cylinder block in which is arranged any desired or suitable number of cylinders 11. The cylinders are provided with a cylinder head 12, secured in position in any suitable manner, such as by means of the usual fastening bolts 13, and a valve plate 14 having suitable valves 15 therein. The head 12 is provided with the usual inlet and discharge outlet openings, one of which, 16, is shown.

Reciprocable in each of the cylinders is a piston

2

17, connected by means of a piston rod 18, to an eccentric strap 19 which co-operates with an eccentric 20 mounted upon the main shaft 21 of the compressor. The shaft 21 is journaled in a suitable bearing 22 in one of the walls of the compressor chamber, and also has a bearing against a suitable ball bearing 23 mounted in a head 24, the latter being secured in position by means of fastening devices 25. The ball bearing 23 has engagement with a suitable bearing plate 26 and also a bearing member 27, the latter being seated in a recess 28 in the end of the shaft 21, and the parts are held in engagement by means of a suitable spring 29. A counterweight 30 may be provided on the shaft 21, to counterbalance the eccentric 20, and a projection 31 may also be provided on the eccentric strap 19, to counterbalance the part and assist in lubricating the parts, as the shaft rotates, by the splash system.

All of the above described parts are of the usual and well-known construction. The shaft 21 projects for any suitable distance beyond the wall 32 of the casing, and is preferably reduced in diameter, as at 33, to form a shoulder 34, against which a member 35 of the shaft seal rests. Encompassing the shaft and resting against the member 35, is another member 36.

The packing type rotary shaft seal comprises a series of members 37—38 of suitable material, and also a washer member 39 constructed of any suitable pliable or resilient material. The seal assembly thus formed is disposed within a cup-shaped casing or housing 40, through the bottom 35 of which the shaft passes. The housing 40 is provided, preferably, with a flanged base 41 that abuts the outer face of the wall 32, a portion of the wall preferably extending into the housing, as at 42. This housing is removably secured in position in any suitable manner, such as by means of fastening bolts 43.

The motor for operating these parts is disposed outside of the compressor casing, and consists, essentially, of a stator member 44, which is held in position in any suitable manner, but preferably by means of a cap member 45, which is of annular construction to provide an opening 46. This cap member is secured to the wall 32 preferably by means of rods or bolts 47 which pass through a flange 48 on the cap member, and are threaded into the wall of the casing, as at 49, nut's 50 being threaded upon the other end of the bolts. This stator member may be of the ordinary and well-known construction, and

the wall 32 of the casing may be provided with a recess 51, into which a portion of the stator member projects, thereby permitting the stator member to be placed in close proximity to the compressor casing.

Rotating within the stator member, is a rotor 52, the hub 53 of which is provided with an open end recess 54. This rotor is sleeved upon the shaft 21, and is held in position, preferably, by means of a suitable key 55. When in position, the casing 48 and enclosed sealing assembly project into the recess 54, and the bottom of the recess 54 preferably rests against a shoulder 56 on the shaft 21. These parts are held in assembled relation, preferably, by means of a nut or collar 57 engaging threads 58 on the shaft.

The extremity of the shaft 21 passes through the opening 46 and beyond the cap member 45, and secured to such extremity is a fan 59 of any suitable construction, and of any desired size. This fan serves as a means for cooling the motor, and, by being mounted upon the main shaft of the compressor, it will be manifest that an extra motor for driving the fan will be dispensed with.

As the compressor operates, the lubricant in the compressor casing will be delivered, by the splash system, into a trough or channel 60, from where it flows through suitable lubricating passages 61 to lubricate the shaft and the rotating parts. A separate suitable screen or tubular housing 62 is provided, which encompasses the motor and is held in position between the cap 45 and the wall 32 of the compressor, by means of the tie rods or bolts 47.

With this improved construction, it will be manifest that outside oiling of the bearings and fan will be eliminated and, by removal of the cap 45, access may be readily had to the motor. The rotor may then be removed, and access may be readily had to the shaft seal. The fan 59 is first removed, being secured to the shaft in any suitable manner, after which the rotor may be removed by removal of the nut or collar 57. Furthermore, the fan 59 also serves to cool the condenser 63, as well as the motor windings.

While the preferred form of the invention has been herein shown and described, it is to be understood that various changes may be made in the details of construction and in the combination and arrangement of the several parts, within the scope of the claims, without departing from the spirit of this invention.

What is claimed as new is:

1. A compressor unit for refrigerating apparatus comprising a housing; a compressor within the housing; a main operating shaft connected with the compressor and having one end extending through and beyond one wall of the housing, said one wall being formed to provide a supporting bearing through which the shaft extends; a packing type rotary seal assembly on the shaft outside the housing and closely adjacent thereto; a casing removably secured to the outside of the housing around the supporting bearing and including an outwardly projecting portion enclosing and supporting said seal assembly; an electric motor having a stator surrounding a rotor, said rotor including a hub secured on said shaft and having an open end recess receiving the sealing assembly; an annular cap member surrounding the shaft and covering the outer end of the motor stator; stator holding rod members detachably securing the cap member to said one wall of the housing and in spaced relation thereto and to the motor stator; and a separate tubular housing

member encompassing the motor and removably mounted between the annular cap member and the said one wall of the housing.

2. A compressor unit for refrigerating apparatus comprising a housing; a compressor within the housing; a main operating shaft connected with the compressor and having one end extending through and beyond one wall of the housing, said one wall being formed to provide a supporting bearing through which the shaft extends; a removable head comprising a part of an opposite wall of the housing, said removable head including a bearing disposed within the housing and receiving the other end of the shaft; a packing type rotary seal assembly on the shaft outside the housing and closely adjacent thereto; a one-piece casing removably secured to the outside of the housing around the supporting bearing and including an outwardly projecting cup-shaped portion enclosing and supporting said seal assembly; an electric motor having a stator surrounding a rotor, said rotor including a hub keyed to said shaft and having an open end recess receiving the sealing assembly; an annular cap member surrounding the shaft and covering the outer end of the motor stator; stator holding bolts detachably securing the cap member to said one wall of the housing and in spaced relation thereto and to the motor stator, said one wall having an outer annular recess disposed inwardly of the seal assembly and receiving the adjacent end portion of the stator with space therearound; a separate screen encompassing the motor and extending between the annular cap member and the said one wall of the housing; and a fan mounted on the end of the shaft a short distance outwardly of the annular cap member.

3. A compressor unit for refrigerating apparatus comprising a housing; a compressor within the housing; a main operating shaft connected with the compressor and having one end extending through and beyond one wall of the housing, said one wall being formed to provide a supporting bearing through which the shaft extends; a removable head comprising a part of an opposite wall of the housing; a resiliently yieldable thrust bearing mounted on said head within the housing and receiving the other end of the shaft; a packing type rotary seal assembly on the shaft outside the housing and closely adjacent thereto; a one-piece casing removably secured to the outside of the housing around the supporting bearing and including an outwardly projecting cup-shaped portion enclosing and supporting said seal assembly; an electric motor having a stator surrounding a rotor, said rotor including a hub keyed to said shaft and having an open end recess receiving the sealing assembly; an annular cap member surrounding the shaft and covering the outer end of the motor stator; peripherally spaced stator holding bolts detachably securing the cap member to said one wall of the housing and in spaced relation thereto and to the motor stator, said one wall having an outer annular recess receiving the adjacent end portion of the stator with space therearound; a separate cylindrical screen encompassing the motor and bolts extending between the annular cap member and the one wall of the housing; and a fan mounted on the end of the shaft a short distance outwardly of the annular cap member.
